UNITED STATES PATENT OFFICE.

EBEN E. FULLER, OF BIG LAKE, ASSIGNOR OF ONE-HALF TO GEORGE HOUGHTON, OF MINNEAPOLIS, MINNESOTA.

BALING-PRESS.

SPECIFICATION forming part of Letters Patent No. 288,987, dated November 20, 1883.

Application filed September 7, 1883. (No model.)

To all whom it may concern:

Be it known that I, EBEN E. FULLER, a citizen of the United States, residing at Big Lake, in the county of Sherburne and State of Minnesota, have invented certain new and useful Improvements in Baling-Presses; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to certain improvements in baling-presses for hay, straw, and other material, and has for its object the provision of a simple, durable, and compact press, the several parts and elements of which are so constructed and disposed with relation to each other as to lighten the machine and increase the strength, while at the same time the parts attached to and operating the plunger are controlled and operated by mechanism adapted to give the greatest possible amount of pressure to the plunger with less motive power than has heretofore been employed to accomplish this purpose.

My invention has, further, for its object the provision of means whereby the bale-binding material shall be passed about the bale when the latter is within the bale-chamber, the ends of said binding material being afterward brought within reach of the operator and secured together, thus avoiding the use of a follower, and enabling each finished bale to operate as a press-head against which the next succeeding bale is formed, and the ejection from the bale-chamber of a compact and securely-bound bale, finished and ready for the market or storage.

The invention further contemplates the accomplishment of the various objects above set forth in such a manner that a finished bale of straw, hay, or other material shall not be cut or otherwise injured by the successive steps through which it passes to attain its finished form.

To the accomplishment of the objects above set forth my invention consists in the construction, arrangement, and combination of the

various parts or elements, substantially as hereinafter described and claimed.

Referring to the drawings, in which similar letters of reference denote like parts, Figure 1 represents a side view of my improved baling-press. Fig. 2 represents a top plan view thereof. Fig. 3 represents a front view of the chain-posts detached from the press. Fig. 4 is a side view of the anchor-timbers of the toggle-jointed timbers by which the plunger is operated. Fig. 5 is a perspective view of one of the toggle-timbers, showing the means by which the toggle-jointed timbers are operated. Figs. 6 to 9, inclusive, represent views of portions of the bail-chamber of the press, and show the manner of introducing and retaining the hay, straw, or other material therein. Figs. 10 to 12, inclusive, represent views showing the means employed to pass the bale-tie about the bale when the latter is within the bale-chamber. Fig. 13 represents the hook employed to pass the tie around the bale. Fig. 14 represents a modified form of the hook shown in Fig. 13.

Referring to the drawings, A represents the bale-chamber, having open ends, sides a , a' , bottom a'' , and top a''' . The sides a , a' thereof are provided with tying-slots a^1 , and its top, near the forward end thereof, with hopper A' , in which the material to be pressed is placed, and from which it passes into the bale-chamber through an opening, A^2 , in the top a''' thereof and in front of a plunger, A^3 , for the purpose of pressing such material.

So far as described my invention is similar to those in use and known to the art under the name of "continuous presses."

I will now proceed to describe the particular parts and construction to which my improvement relates.

The main sills B, B' of the press are extended forward to a considerable distance beyond the bale-chamber, as shown, and are provided at such extended portion, and the outside thereof, with timbers B'', B''' that are parallel with the sills B, and are connected thereto by blocks B'' and bolts b, as shown.

C represents posts extending upwardly from each of the main sills B and the timbers B'', (see Fig. 3,) said posts C being firmly secured

at their upper ends to a cross-timber, C', which extends from side to side of the press, straining-rods C² being attached by eyebolts c to the sills B, and thence pass over the top of the timber C', and thus serve to further strengthen and support the uprights C. The rods C² are each provided with swivels c', having female screws in their ends, into which male screws upon rods take, and by which any desired degree of tension may be given to the rods.

D D' represent timbers pivoted together at d, and form, when pivoted to a proper support and plunger, the means by which said 15 plunger is operated. The forward end of this timber D is pivoted by means of a bolt, e, between anchor-timbers E, which are secured to cross-timbers E', extending from one to the other of the sills B.

20 e' represents additional braces or straining-rods, which extend from the posts C around the bolt e, at each side of the timber D, and to one of the cross-timbers E', each end of the rod e' being provided with a nut and screw, as shown. The rear end of the timber D is provided upon its lower edge with an offset, d', the lower surface of which is cut away, so that when the plate d² is secured thereon a slot, d³, is formed, for the purpose hereinafter 25 to be described. The timbers D' are pivoted near the rear ends thereof, at a⁴, to the plunger A³, and are provided near their forward ends with a pivotal bolt, d', to which are pivoted the ends of the levers which operate the folder F, one of said levers, F', being in angular 30 form, as shown, and pivoted at f between posts F', the end of the lever F' that connects with the timber D' being provided with a slot, f', in which the pivotal bolt d' slides when the 40 press is operated, as shown in Fig. 1. The lever F' is connected to the folder at about the middle of the latter.

45 F³ represents a link or connecting-rod connected at one end to the top of the folder and at the other end to the pivotal pin d', its purpose being to limit the sway of the folder, as shown in Fig. 1. The posts F', between which the lever F' is pivoted, form the rear parts of the bale-chamber, and are extended upwardly 50 to provide a bearing for said lever.

G represents the main driving-shaft, journaled in suitable boxes, g, upon the sills B'. The shaft G extends across the press, and is provided upon one end with a driving-pulley, G', and upon the other end with a balance-wheel, G². G³ represents geared pinions mounted upon the shaft G between the sills B and timbers B', and engage with and rotate geared spur-wheels G⁴, mounted upon short 55 shafts G⁵, journaled in boxes g' upon the sills B B', the inner end of each of the shafts G⁵ being provided with sprocket-wheels H, which are connected by sprocket-chains H' with similar sprocket-wheels, H², mounted upon short 60 shafts h, journaled in suitable boxes in the forward edges of the timbers or uprights C.

h' represents a bar or rod which passes from one to the other of the chains H' through the slot d³ of the timber D. A sleeve, h², is placed upon the rod, as shown in Fig. 5.

70 From the above-described construction it will be seen that when the driving-shaft is rotated it will, through the spur-wheels G³ G⁴ and sprocket-wheels H H', cause the chain H' to pass around said sprocket-wheels, and said chain will, through the rod h', cause the lever D to rise and fall, thus moving the plunger back and forth in the bale-chamber, and at the same time operate the folder F, as hereinbefore described.

I represents a retainer pivoted at i near the rear side of the aperture in the top of the bale-chamber, the operation thereof being clearly shown in Figs. 6 to 9, inclusive. A spring, i', serves to throw the rear edge of the retainer 85 down, as shown in Fig. 6, in which figure the material to be pressed is represented as about to enter the bale-chamber. Fig. 7 shows the folder F as pressing said material downward into the bale-chamber. Fig. 8 shows the plunger in the act of pressing such material into the bale-chamber past the retainer I, which is at this time closed up; and Fig. 9 shows the plunger withdrawn from the pressed material, which is held in position by the retainer. 90

95 As a rule, baling-presses, and more particularly those of the class known as "continuous presses," have been and are provided with followers—i. e., removable partitions—which are placed between the bales within the bale-chamber, and such followers have been provided with grooves to permit the passage of the tie, such ties being separate from the press or not attached thereto.

100 My invention contemplates, first, the provision of means whereby the tie is attached to the press and made to operate in lieu of the follower above referred to; and, secondly, the provision of means whereby said tie may be passed around the bale and its ends brought 110 within easy reach of the operator while the bale is within the chamber. I accomplish this purpose in the following manner, to wit:

115 K represents spools mounted in suitable supports, K', at one side of the bale-chamber, near the feed-opening thereof, the ends of the binding material therein being passed across the press and made fast to pins k' upon the opposite side of the press and within easy reach of the operator, as shown in Fig. 10. The 120 first bale is now formed against such binding material, pressing it into the position shown in Fig. 11. When enough material has been 125 pressed to form a bale of the proper size, a rod, L, provided at its end with a hook, is inserted through the tying-slots from the side opposite to that containing the spools, and catches the binding wire or cord, which is drawn through the press and cut at the loop, as shown in Fig. 12. The binding material is 130 passed around each succeeding bale in the manner above described, each bale acting as

a press-head against which the succeeding bale is formed, thus dispensing with the use of followers or partition-boards. The rod L normally rests in supports M, attached to the 5 side of the press, and such supports operate as guides when the rod is to be passed through the press. If desired, two or more rods may be connected to a handle common to all, and may thus be operated at one and the same 10 time. This construction is shown in Fig. 14.

The operation of the press will be understood without further description.

I do not confine myself to the exact form and construction of parts shown in the drawings 15 and herein particularly described, but hold myself at liberty to make such changes in details of construction as fairly fall within the scope of my invention.

Having thus described my invention, what 20 I claim is—

1. A baling-press for hay, straw, and other material, constructed as described, having the bale-chamber A, operated by toggle-timbers D D', rod h', sprocket-chain H', connecting 25 the sprocket-wheels H H², and means for driving the same, whereby the plunger A³ is caused to move back and forth within the bale-chamber, as and for the purpose set forth.

2. In a baling-press for hay, straw, and 30 other material, the bale-chamber having sills B, which project forwardly beyond the end of said bale-chamber, and are provided with anchor-timbers E, in combination with the tog-

gle-timbers D D', operated by means substantially such as described, folder F, and levers 3 5 F' F³, as and for the purpose set forth.

3. In a baling-press for hay, straw, and other material, the bale-chamber A, having sills B, which project forwardly beyond the end of said bale-chamber, and are provided 40 with supplemental sills B', anchor-timbers E, and uprights C, in combination with the toggle-jointed timbers D D', operated by means substantially such as described, levers F' F³, and folder F, as and for the purpose set forth. 45

4. In a baling-press for hay, straw, and other material, the bale-chamber A, having sills B B', anchor-timbers E, and uprights C, in combination with the toggle-timbers D D', operated by the sprocket-chain H', bar or rod 50 h', connecting the sprocket-wheels H H², and spur-wheels G³ G⁴, substantially as described.

5. The combination, in a baling-press for hay, straw, and other material, of the bale-chamber A, having sides a, provided with tying-slots a³, and supports M, adapted for guiding the hooks L to facilitate the drawing of the binding material around the bale when the latter is in the bale-chamber. 55

In testimony whereof I affix my signature in 60 presence of two witnesses.

EBEN E. FULLER.
